UNITED STATES PATENT OFFICE.

MALCOLM MCKELLAR, OF NESBITT, CANADA.

CLOTH-MEASURING DEVICE.

SPECIFICATION forming part of Letters Patent No. 746,984, dated December 15, 1903.

Application filed March 9, 1903. Serial No. 146,815. (No model.)

To all whom it may concern:

Be it known that I, MALCOLM MCKELLAR, a subject of the King of Great Britain, residing at Nesbitt, county of Brandon, Province 5 of Manitoba, Canada, have invented certain new and useful Improvements in Cloth-Measuring Machines; and I do hereby declare that the following is a full, clear, and exact description of the invention, such as will enable 10 others skilled in the art to which it appertains to make and use the same.

My invention relates to machines for measuring fabric, and it is expected to be especially useful in wholesale houses, factories, 15 &c., which must supply cloth to customers.

The invention consists in the construction and combination of parts to be more fully described hereinafter and definitely set forth in the claims.

20 In the drawings, which fully illustrate my invention, Figure 1 represents the device in side elevation. Fig. 2 represents the machine in plan, the web of cloth represented being shown as broken away to more clearly disclose the construction of the mechanism. Fig. 3 is a transverse vertical section taken substantially on the line 3-3 of Fig. 1. Fig. 4 represents in perspective a portion of the table included in the device and showing a 25 support for the cloth-roll. Fig. 5 is a vertical section taken substantially upon the line 5-5 of Fig. 2, but upon a somewhat enlarged scale. Fig. 6 represents in perspective a portion of the mechanism for guiding the web of cloth as it passes. Fig. 7 represents also in 30 perspective another portion of the mechanism for guiding the web of cloth. This view represents the parts in an inverted position. Fig. 8 represents in perspective one of the 35 gudgeons which I use in connection with the apparatus.

Throughout the drawings and specification the same numerals of reference denote like parts.

40 Referring more particularly to the parts, 45 represents a substantial table supported upon suitable legs 16, as indicated. Preferably at substantially its middle point this table is provided with a pair of oppositely-disposed 50 standards 17, which constitute supports for a measuring-drum 18, mounted between the same. This drum may be provided with a

suitable axle or arbor 19, the extremities of which are held in the inclined slots 20, formed in the side of the standards 17 in the manner 55 shown. At their upper portions the standards 17 are provided with vertically-disposed slots or openings 21, in which are guided blocks 22, which blocks constitute bearings for the reduced extremities of a presser-roller 60 23, which is disposed between the supports, as indicated. These blocks 22 are provided with vertically-extending stems 24, which pass through the upper wall of the slots 21, and around these stems there are coiled helical springs 25, which thrust downwardly 65 against the blocks 22, so that the presser-roller 23 is constrained in a resilient manner against the upper face of the aforesaid measuring-drum 18.

70 At its opposite ends the table 15 is provided with transverse guiding-grooves 26, which constitute shears upon which are mounted pillow-blocks or pedestals 27 and 30, respectively, which have openings 28, conforming substantially to the outline of the table ends, as shown. It should be understood that these pillow-blocks are adapted to slide laterally of the table upon the shears 26, and they may be clamped in any position 80 desired by means of the thumb-screws 29.

75 It should be understood that the pairs of pillow-blocks 27 and 30 support between them, respectively, the rolls 31 32 of the material which is being measured, so that the 85 web 33 of the material lying between the two rollers passes over the upper surface of the measuring-drum, passing between it and the aforesaid presser-roller 23 in the manner indicated. The fabric represented as being 90 measured is supposed to be ordinary cloth, and it will be remembered that these rolls are usually formed by winding the material around a board 39. These boards 39 are supported between gudgeons 34, which comprise 95 diverging jaws 35, adapted to receive the ends of the boards, as shown. They comprise also necks or shanks 36, which constitute journals mounted in the pillow-blocks, so that the rolls are rotatably supported, as 100 will be readily understood. To this end the pillow-blocks 27 and 30 are provided with openings 37, in which are mounted blocks 38 39, which lie, respectively, below and above

the journals 36 and constitute bearings therefor. The upper blocks 39 are adapted to be forced downwardly against the journals by means of clamping-screws 40, carried in sleeves 10, whereby a frictional resistance 5 may be offered to the rotation of the rolls. It should be understood that the material is to pass in the direction of the arrow, and for the purpose of winding it upon the roll 32 10 one of the gudgeons of this roll is provided with a square extremity 41, to which is attached a suitable crank 42. As the web passes from the measuring-drum 18 it runs under a horizontal guide-roller 43, suitably 15 mounted between the supports 44, bolted to the table in the manner indicated. At the opposite side of the drum the web passes under a tension-roller 45, the arbor 46 of which has its extremities mounted in a vertically-disposed slot 47, formed in the standards 48, which are secured to the table 15 in the manner indicated. It should be understood 20 that this tension-roller constitutes also a guide-roller for the web, and it should be 25 stated that by reason of the fact that it is free to move vertically its weight operates to maintain the web in a taut condition as it passes over the measuring-drum 18, and in this manner inaccuracies of measuring 30 will be averted. This tension-roller 45 has been shown in its extreme elevated position. As the web 33 passes from the horizontal 35 guide-roller 43 it passes between the vertical guide-rollers 49, of which there are two disposed oppositely, as indicated. These rollers 49 are provided with bores 50, which enables them to be loosely mounted upon vertically-disposed studs 51. These studs are mounted, respectively, in plates 52 53, which are substantially 40 of the construction shown in Figs. 6 and 7. It should appear that the plate 52 comprises a boss or projection 54 on its upper side, while the plate 53 comprises a boss 55 upon its lower side. It should be observed 45 that the plates are provided with elongated openings or slots 56 57 in the manner shown. It should be understood that these slots are of substantially the same width and are adapted to constitute guides, respectively, for the 50 projections 55 and 54 when the two plates are properly applied to each other, as will be readily understood and as indicated in the figure. The studs 51 aforesaid may be provided with enlarged heads 58 at their lower extremities, 55 which are countersunk, as indicated, into the lower faces of the plates 52 and 53. A clamping-bolt 59 passes through the alining slots 56 and 57 and is adapted to clamp the plates together and hold them firmly upon the table, 60 a suitable wing-nut 60 being provided for this purpose.

The measuring-drum 18 I prefer to make just one yard in circumference. One of its end faces is provided with a pin 61, which describes a circle about the axis of the drum as the same rotates. At every revolution this pin comes into contact with the edge of a

counter-wheel 62, which it advances through one unit or graduation to indicate the amount of cloth measured. This counter-wheel may 70 be loosely mounted upon a fixed stud 63, which stud carries rigidly a pointer 64, which indicates where the reading is to be taken.

It should be observed that the length of the rollers 43 and 45 is substantially the same 75 as that of the measuring-drum 18, and it should be understood from the construction of the apparatus described that the pillow-blocks 27 and 30 can be adjusted into any desired distance apart, so that cloth of various widths may be readily measured. It should also appear that the construction of the parts in connection with the vertical guide-rollers 49 enables a similar adjustment 80 in width to be effected with respect to them. 85

While I have shown in the accompanying drawings the preferred form of my invention, it will be understood that I do not limit myself to the precise form shown, for many of the details may be changed in form or position without affecting the operativeness or utility of my invention, and I therefore reserve the right to make all such modifications as are included within the scope of the following claims or of mechanical equivalents 90 to the structures set forth. 95

Having thus described my invention, what I claim as new, and desire to secure by Letters Patent, is—

1. In a cloth-measuring machine, in combination, a measuring-drum, means for passing a web of material over the surface of the same, a pair of laterally-disposed plates, guide-rollers carried thereby and disposed substantially at right angles to the axis of said drum, and means for adjusting said plates laterally with respect to said web. 100

2. In a cloth-measuring machine, in combination, a measuring-drum, means for passing a web of material over the surface thereof, 110 a table upon which said drum is mounted, a pair of plates, guide-rollers carried respectively thereby and disposed substantially at right angles to the path of said web, means whereby said plates may be adjusted laterally with respect to said web, and means for locking said plates simultaneously to said table. 115

3. In a cloth-measuring machine, in combination, a table, a measuring-drum supported thereby, means for passing a web of material over said drum, a pair of plates disposed laterally with respect to said web, rollers carried respectively by said plates and adapted to guide said web laterally, 120 means for guiding said plates one upon the other, and a bolt adapted to clamp said plates to said table. 125

4. In a cloth-measuring machine, in combination, a table, a measuring-drum carried thereby, means for passing a web of material over said drum, a pair of plates disposed laterally with respect to said web, rollers carried respectively by said plates and disposed sub- 130

stantially at right angles to the path of said web, means for guiding said plates one upon the other, said plates having registering elongated openings, and a bolt passing through said openings and adapted to clamp said plates to said table.

5. In a cloth-measuring machine, in combination, a table, a measuring-drum carried thereby, means for passing a web of material over said drum, a pair of plates disposed laterally with respect to said web, vertical studs carried by said plates, removable rollers carried respectively by said studs

and disposed substantially at right angles to the path of said web, means for guiding 15 said plates one upon the other, said plates having registering elongated openings, and a bolt passing through said openings and adapted to clamp said plates to said table.

In witness whereof I have hereunto set my 20 hand in the presence of two witnesses.

MALCOLM MCKELLAR.
